(57) **CLAIM**

We claim the ornamental design for a toothbrush handle, as shown and described.

DESCRIPTION

The file of this patent contains at least one drawing executed in color. Copies of this patent with color drawing(s) will be provided by the Office upon request and payment of the necessary fee.

FIG. 1 is a perspective view of a toothbrush handle according to a first embodiment;

FIG. 2 is a front view thereof;

FIG. 3 is a back view thereof;

FIG. 4 is a right side view thereof;

FIG. 5 is a left side view thereof;

FIG. 6 is a bottom view thereof;

FIG. 7 is a top view thereof;

FIG. 8 is a perspective view of a toothbrush handle according to a second embodiment;

FIG. 9 is a front view thereof;

FIG. 10 is a back view thereof;

FIG. 11 is a right side view thereof;

FIG. 12 is a left side view thereof;

FIG. 13 is a bottom view thereof;

FIG. 14 is a top view thereof;

FIG. 15 is a perspective view of a toothbrush handle according to a third embodiment;

FIG. 16 is a front view thereof;

FIG. 17 is a back view thereof;

FIG. 18 is a right side view thereof;

FIG. 19 is a left side view thereof;

FIG. 20 is a bottom view thereof;

FIG. 21 is a top view thereof;

FIG. 22 is a perspective view of a toothbrush handle according to a fourth embodiment;

FIG. 23 is a front view thereof;

FIG. 24 is a back view thereof;

FIG. 25 is a right side view thereof;

FIG. 26 is a left side view thereof;

FIG. 27 is a bottom view thereof;

(Continued)

FIG. 28 is a top view thereof;
 FIG. 29 is a perspective view of a toothbrush handle according to a fifth embodiment;
 FIG. 30 is a front view thereof;
 FIG. 31 is a back view thereof;
 FIG. 32 is a right side view thereof;
 FIG. 33 is a left side view thereof;
 FIG. 34 is a bottom view thereof; and,
 FIG. 35 is a top view thereof.

The broken lines shown in the figures depict portions of the toothbrush handle and form no part of the claimed design.
